UNITED STATES PATENT OFFICE

HARRY L. LIBERA, OF WINONA, MINNESOTA

BASKET

Application filed April 13, 1929. Serial No. 354,822.

This invention relates to a basket or means adapted to be suspended from a banana stem or stalk for the purpose of supporting loose bananas, fruits or other articles.

It is primarily aimed to provide a novel means whereby space may be conserved in the display of bananas in that the basket or container may be suspended from one banana stalk and have bananas which have been removed from another stalk or stalks displayed therein.

It is further aimed to provide a construction whereby the basket or means is attached to the stalk by elements which will offer no interference with each other or injure the bananas incidental to attachment of the basket.

A further object is to provide a construction wherein the basket has a multiplicity of attaching arms secured thereto so that they may have a diametric movement and a lateral movement and also have attaching portions arranged at different elevations in order to accomplish the ends heretofore mentioned.

The more specific objects and advantages will become apparent from a consideration of the description following, taken in connection with the accompanying drawings illustrating an operative embodiment.

In said drawings:

Fig. 1 is a view illustrating the improved basket in side elevation suspended from a banana stalk, the latter being fragmentarily shown.

Fig. 2 is a plan view of the basket, and Fig. 3 is a sectional view taken on the line 3—3 of Fig. 2.

Referring specifically to the drawings, the basket, receptacle, or supporting body is shown at 10 and may be of any preferred construction. By way of example, it is of skeleton wire form having an upper ring 11 provided with equidistantly spaced eyelets or loops 12.

Attaching arms for the basket 10 are shown at 13 and are preferably made from relatively stout metallic wire of a heavier gauge than the parts of the basket. The arms 13 at their lower ends have outwardly inclined portions

14 terminating in eyelets 15 which engage the eyelets 12 as shown, and thus loosely and pivotally connect the arms 14 to the basket in such a manner that the arms may freely move radially of the basket and also have a lateral swinging movement from the eyelets 12. The offset or inclined portions 14 aid in enabling the arms 13 to be located within the basket 10 when disengaged from the banana stalk, and particularly in transportation, so that a number of the baskets in effect may be nested. The folded position of the arms 13 is shown in dotted lines in Figs. 1 and 2.

While four of the arms 13 are shown, it is obvious that the number may be increased or decreased, depending upon the size of the basket or weight to be supported.

Said arms 13 have vertical portions 16 which constitute handles and from which inwardly extending attaching portions 17 branch.

Each attaching portion 17 is arranged at a different elevation so that the same will occupy different planes, as well shown in Figs. 1 and 3. Also, in the attached position, the portions 17 at their inner ends overlap each other as also shown in said Figures 1 and 3. The free ends of the attaching portions 17 are provided and deflected downwardly along a gradual curve or otherwise, as at 18, and the under surfaces thereof are preferably toothed or serrated as at 19.

The portions 18 are adapted to be thrust into the stalk 20 of a bunch of bananas, generally shown at 21.

By reason of the construction described, each portion 18 will extend completely through the stalk 20 and be disposed in a different plane, all at a different elevation so as not to interfere with one another or unduly weaken the stalk 20 at the zone of attachment of said portions 18. The radial and lateral movement necessary to the attachment of portions 17 is provided at the hinge connections 14—15. Such movement also enables the portions 17 to be manipulated in order to be thrust intermediate or between the various bananas on the stalk in such a way as not to penetrate or injure them. During

the application of the arms 12 to the banana stalk or removal of the same therefrom, the arms are grasped and manipulated by the handle portions 16.

5 The basket or supporting body 10 may be used for any desired purpose but primarily is adapted to support loose bananas which have been removed from another stalk or stalks, in order to conserve space in the display of the bananas and in order to provide 10 a more attractive display by avoiding undue exposure of a banana stalk.

If desired, the basket or body 10 may be used for sign display purposes to which end 15 one or more signs 22, of any desired form, may be attached to the basket in any approved manner, which signs may contain matter relating to the bananas, or any other desired subject.

20 The deflection of the portions 18 and tooth-ing thereof at 19 aids in preventing accidental detachment of the arms from the stalk 20.

Various changes may be resorted to provided they fall within the spirit and scope 25 of the invention as defined by the appended claims.

I claim as my invention:

1. An article adapted to be suspended having 30 supporting arms, said arms at a distance above their lower extremities having attaching portions and applicable to a support through movement in different directions and arranged in different planes.

35 2. An article adapted to be suspended having supporting arms, said arms at a distance above their lower extremities having attaching portions independently applicable to and removable from a supporting means and arranged at different elevations and angles.

40 3. An article adapted to be suspended having supporting arms, said arms having disaligned attaching portions adapted to overlap.

45 4. An article adapted to be suspended having freely movable supporting arms, said arms at a distance above their lower extremities having attaching portions independently applicable to and removable from a supporting means, the movement permitting the attaching portions to be disaligned in attached position.

50 5. An article adapted to be suspended having supporting arms, means pivotally mounting said arms to enable disposition of their attaching portions one over the other.

55 6. An article adapted to be suspended having supporting arms mounted for free movement relatively to each other, each of said 60 arms having an attaching portion deflected out of a straight line, the mounting of the arms enabling the attaching portions to overlap in attached position.

65 7. An article adapted to be suspended having supporting arms each provided with an

attaching portion, means mounting the arms whereby the attaching portions may have axial and lateral movement to enable attachment thereof one above the other.

8. An article adapted to be suspended comprising a receptacle, attaching arms independent of each other, said arms at their lower ends being loosely connected to the receptacle, said arms having portions extending upwardly and inwardly from the receptacle, handle portions extending upwardly from the first mentioned portions, and attaching portions extending inwardly from the handle portions.

70 9. An article adapted to be suspended comprising a basket having eyelets, supporting arms generally of L-shape to provide attaching portions and handle portions, deflected portions extending from the handle portions and provided with eyelets pivotally connected to the first mentioned eyelets, the free ends 75 of the attaching portions being adapted to overlap and being deflected out of a straight line.
